UNITED STATES PATENT OFFICE.

ISAAC L. KISER, OF LITTLE ROCK, ARKANSAS.

CAR-COUPING.

SPECIFICATION forming part of Letters Patent No. 690,297, dated December 31, 1901.

Application filed July 8, 1901. Serial No. 67,472. (No model.)

To all whom it may concern:

Be it known that I, ISAAC L. KISER, a citizen of the United States, residing at Little Rock, in the county of Pulaski and State of Arkansas, have invented new and useful Improvements in Car-Couplings, of which the following is a specification.

This invention relates to car-couplings, and in some respects it is an improvement upon the coupling set forth in a contemporaneously-pending application, Serial No. 60,761, filed May 17, 1901; and one of the objects of the invention is to provide a simple device of this character wherein friction is greatly reduced and which is automatic in action and especially intended for application to passenger-cars.

The improved knuckle hereinafter described is applicable, of course, to draw-heads of the kind disclosed in said application and, like such prior knuckle, it is of the duplex type, it having complementary jaws at its opposite ends, so that if the knuckle be broken or in any wise injured it can be reversed and rendered just as useful as a new one. The draw-head in the present case has three sets of vertically-alined or registering holes to receive one or two locking-pins, so that when necessary the knuckle can be dead-locked. The draw-head incloses the lock for the knuckle, and in this application this lock is lifted to release the jaw by means situated below the latter.

The invention is clearly shown in the accompanying drawings, forming a part of this specification, in which—

Figure 1 is a plan view of a car-coupling involving my present improvements and showing the equalizer. Fig. 2 is a face view of the same with the duplex coupling-jaw removed from the draw-head. Fig. 3 is a transverse section taken in the line 3 3, Fig. 2. Figs. 4 and 5 are perspective views of the duplex jaw and locking member therefor detached. Fig. 6 is a horizontal under side sectional view of the draw-head.

Like characters refer to like parts in all the figures of the drawings.

The draw-head is denoted by 12 and is formed at the forward end of a draw bar or stem, as 13.

The coupling member, which is made of

standard dimensions, so as to adapt it for operation in connection with any of the automatic couplings now in use, is designated by 14, and it comprises two similar jaws, as 15 and 16, and it has a central hole, as 17, to receive a pivot-pin, hereinafter described, and pin-holes, as 18, in the complementary end jaws, all of said holes being perpendicularly disposed. The said duplex coupling-jaw is symmetrically formed throughout its entire length and what is for the time being the inner jaw constitutes, in effect, a knuckle. The draw-head has projecting walls 60, horizontally located one above the other and which house the projecting parts of the duplex jaw, thereby avoiding any friction, and what are shown as the right ends of these projecting walls have sloping or slanting guide-surfaces, 70 as 61, the upper one being inclined upward and the lower downward. These sloping surfaces better enable the coupling of cars when the draft-lines thereof are not equal.

The duplex jaw or coupling member 14 has 75 centrally thereof the vertical lip or extension 62, the function of which is to make the said jaw operate more easily and accurately, it being seen that said lip or extension is of the same height as the jaw.

The draw-head has two pin-holes, as 20 and 21, the first-mentioned one being adapted to register with what is the rearmost hole of the duplex jaw when the same is closed. Should the forward or pivot hole break out, all that 85 is necessary to safely transport the car to the end of the journey is to place a pin through the rear registering holes, so as to dead-lock the jaw.

The duplex coupling-jaw swings upon the 90 central pivot-pin 14', and should one of its jaws become worn or broken from any cause this pivot-pin can be removed and the jaw reversed, whereby, in effect, a new part is secured.

The draw-head and coupling-jaw with respect to the holes just set forth are similar to those set forth in my said prior application; but in the present case I form in the draw-head a third hole, as 63, and it will be seen 100 that these holes are triangularly arranged. This hole 63 is adapted to receive a pin, (not shown,) which is passed through the working end or jaw of the duplex coupling-jaw inter-

locked with the one illustrated, and the insertion of this pin secures a dead-lock without any delay in case the knuckle or jaws in either draw-head become totally disabled.

5 The locking member for the jaw is denoted by 22, and it comprises a back piece, as 23, which may be of rectangular plate form, which is vertically slidable in a substantially similar shaped depression or hollow in the 10 rear wall of the chamber of the draw-head, and the opposite side walls of the depression guide said back piece. One of the walls of this depression is shown as beveled and as fitting over the correspondingly-shaped edge 15 of the back piece, so as to limit the oscillation of the latter. The back piece 23 has on its forward face the flanges 24, approximately triangular in shape, and one edge of each flange is rounded, as at 24', to engage against 20 the correspondingly-rounded surface of the inner jaw of the duplex coupling member 14, so as to lock and firmly hold the same. The top wall of the chamber of the draw-head has a pocket, as 25, shaped to agree in outline 25 with the superposed flanges 24, and the lower flange is adapted to receive the upper threaded end of a pin, as 26, depending from the locking member and extending through a suitably-placed perforation in the under side 30 of the draw-head.

To release the duplex coupling-jaw 14, the locking member 22 will be lifted by an upward thrust on the pin 26, as hereinafter described, until the upper flange 24 is carried 35 into the pocket 25. This will bring the lower flange into horizontal line with the transverse opening or aperture 27 of the inner jaw, so that the coupling member will be released and can be swung open, and as it does it sustains 40 the locking member. When the said duplex coupling member 14 is closed, the part 22 drops, so as to lock said member 14.

The lower end of the pin 26 is bifurcated, as at 64, to straddle the short arm of an angle-lever 65, fulcrumed upon a bracket, as 66, depending from the under side of the draw-head. This lever is supported by a cotter-key bolt, as 67, and may be operated by a rod (not shown) mounted upon the car in some 45 suitable place and manner. When the long arm of said lever is swung outward, the pin 26 is raised, so as to lift the locking member 22, and thereby release the compound jaw 14.

The stem or bar 13 is hollow, and at the inner and reduced end of the same are two seats, as 68, each having two holes, as 69, therein, this construction being for the purposes of attaching wrought-iron or steel bars for extending the stem to any length desired.

60 In Fig. 1 I have shown an equalizer; but as the same forms no part of the invention forming the basis of the appended claims it is not illustrated in detail.

By the use of my improved coupler in case 65 of derailment the train would continue coupled after derailment and prevent the cars

from scattering or angling, and it has also a tendency to keep the cars in line.

Various changes within the scope of the appended claims may be made.

Having described the invention, I claim—

1. In a car-coupling, a draw-head having at least three triangularly-disposed pin-receiving holes one of them being situated at the rear of the other two and the outer one of the two forward ones serving to receive a pivot-pin for a coupling member while the inner one serves to receive a locking-pin for a second coupling member arranged to interlock with the first-mentioned coupling member. 70

2. In a car-coupling, a draw-head having at least three triangularly-disposed pin-receiving holes one of them being situated at the rear of the other two and the outer of the two forward ones serving to receive a pivot-pin 75 for a coupling member while the inner one serves to receive a locking-pin for a second coupling member arranged to interlock with the first-mentioned coupling member and the upper and lower walls of the draw-head being extended and the inner forward hole being in said extended walls and the latter serving as a bearing for said second coupling member. 80

3. In a car-coupling, a draw-head having at least three triangularly-disposed pin-receiving holes one of them being situated at the rear of the other two and the outer one of the two forward ones serving to receive a pivot-pin for a coupling member while the inner one serves to receive a locking-pin for a second coupling member arranged to interlock with the first-mentioned coupling member, combined with a coupling member carried by said draw-head said coupling member having duplicate jaws at its opposite end and a central opening to receive a pivot-pin 90 upon which said coupling member swings and said duplicate jaws having pin-receiving openings and the opening in the normally inner jaw being arranged to register with the rear one of said triangular openings when the coupling member is closed. 95

4. In a car-coupling, a draw-head provided with a coupling member having similar jaws at its opposite ends said member being pivotally supported substantially centrally between said jaws and having a lip near its center the lip being of the same height as the coupling member. 100

5. In a car-coupling, a draw-head provided with a coupling member having similar jaws at its opposite ends and pivotally supported substantially centrally between said jaws, a locking member for said coupling member, having a depending pin bifurcated at its lower end, and a lever fulcrumed upon the draw-head one end of which is straddled by the bifurcation of said pin. 115

6. In a car-coupling, a draw-head having at least three triangularly-disposed pin-receiving holes one of them being situated at the

rear of the other two and the outer of the two forward ones serving to receive a pivot-pin for a coupling member while the inner one serves to receive a locking-pin for a second coupling member arranged to interlock with the first-mentioned coupling member and the upper and lower walls of the draw-head being extended and the inner forward hole being in said extended walls and the latter serving as a bearing for said second coupling member, and having oppositely-inclined beveled faces.

7. In a car-coupling, a coupling member

having duplicate jaws at its opposite ends, a central hole and a lip projecting centrally 15 from one of the side faces thereof, the jaws also having holes located at equidistant points from said central hole.

In testimony whereof I have hereunto set my hand in presence of two subscribing witnesses.

ISAAC L. KISER.
